FLUSH CONSTRUCTION RANGE

Filed July 25, 1928

F1 - 1

UNITED STATES PATENT OFFICE

HERMAN H. HEIDBREDER, OF QUINCY, ILLINOIS, ASSIGNOR TO CENTRAL PATTERN COMPANY, OF QUINCY, ILLINOIS, A CORPORATION OF ILLINOIS

FLUSH CONSTRUCTION RANGE

Application filed July 25, 1928. Serial No. 295,179.

This invention relates to a range or cook stove in which any desirable fuel may be used, and it is among the objects of the invention to eliminate the objectionable overhang on the top of the stove where dirt and other matter collects, to eliminate objectionable cracks or crevices at all joints, including the splasher, where grease and dirt are apt to collect and to provide a smooth sanitary structure that is substantially flush at the joints, so that the stove can be easily kept clean and whereby the chances of injuring the hands in cleaning the stove are largely eliminated. It is a further object of the invention to provide a utility drawer in the bottom of the stove where utensils may be kept.

The invention comprises the novel structure and combination of parts hereinafter described and more particularly pointed out and defined in the appended claims.

In the accompanying drawings which illustrate a preferred form of this invention and in which similar reference numerals refer to similar features in the different views:

25 Figure 1 is an elevational view of a stove involving this invention;

Figure 2 is an enlarged fragmentary sectional view taken upon the line II—II of Figure 1 illustrating the flush construction of the 30 range;

Figure 3 is an enlarged fragmentary sectional view taken upon the line III—III of Figure 1, and

35 Figure 4 is an enlarged sectional view taken upon the line IV—IV of Figure 1.

As illustrative of this invention, there is shown a stove having a top 1 with a marginal depending bead 2, shown in this instance with an outer arcuate surface which may be straight or beveled if so desired, and a straight inner edge which also may be curved or beveled if so desired. The front frame or apron 3 of the stove has an upper rabbeted edge 4 terminating in a lower shoulder or lip 5 which abuts the bead 2 with the rabbeted edge secured to the interior straight surface of the bead whereby a substantially flush construction is secured. The apron 3 has an inwardly dished surface which may, of course, be made straight if desirable, with

an inwardly offset ledge 6 for receiving the oven door 7. The lower front part of the frame 3 of the range has an inwardly offset ledge 9 for receiving the door and the bottom of the frame 3 is substantially flush with the base of the range. The front frame of the stove including the apron are also flush with the sides of the stove as shown in Figure 1.

In the bottom of the stove or range, there is a utility drawer 10 in which utensils may be kept. It should be noted that the drawer 10 is so constructed as to augment the flush appearance of the front frame as a whole, and is spaced above the lower termini of the legs so as to be clear of whatever surface the legs rest upon and to facilitate expeditious cleaning of this surface.

From the top of the stove, there rises a vertical plate which forms a splash 11 to which arcuate brackets 12 are secured. The bracket and splash have rearwardly directed attaching flanges 13 and 14 which may be secured together in any suitable manner, as by bolts 15. The splash and bracket are flush with each other and the joint therebetween is very close and scarcely perceptible. The arcuate brackets are also gradually expanded at their lower extremities so as to engage the top of the stove at an angle. Of course, if so desired, the brackets may be integral with the splash.

According to this construction, the range presents a smooth and neat appearance free from cracks or crevices, whereby the accumulation of dirt and grease is prevented. In addition, the objectionable front and end overhang is eliminated and smooth flush construction is secured.

I am aware that many changes may be made and numerous details of construction may be varied through a wide range without departing from the principles of this invention and I, therefore, do not purpose limiting the patent granted hereon, otherwise than necessitated by the prior art.

I claim as my invention:

1. In a range construction, the combination of a front frame having a forwardly protecting lip formed adjacent its upper edge,

and a top portion having a depending marginal bead engaging said lip to form a smooth joint, said bead being arranged to overhang said lip for protecting the joint so formed.

5 2. In a range construction, a splasher formed of a vertical plate, and brackets each presenting an arcuate surface connected to the lateral edges of said plate in such a manner as to form a flush joint, the forward surfaces of said brackets and plate presenting a unit surface free from sharp corners and angles.

10 3. A range comprising a horizontal top, a vertically arranged splasher secured to said top having curved end portions, said end portions being gradually expanded to engage said top at an angle.

15 4. In a range construction, a splasher formed of a vertical plate, arcuate brackets 20 at the lateral edges of said plate, the contiguous edges of said plate and brackets being rearwardly deflected to form cooperating flanges, and means for clampingly securing said flanges together to form close 25 jointures between the contiguous edges of said brackets and plate, the forward surfaces of said brackets and plate, at said jointures being flush.

30 In testimony whereof I have hereunto subscribed my name at Quincy, Adams County, Illinois.

HERMAN H. HEIDBREDER.
